US00D985075S

(12) **United States Design Patent** (10) **Patent No.:** **US D985,075 S**
(45) **Date of Patent:** **** May 2, 2023**

(54) **TOY GUN**

(71) Applicant: **Shijun Lin**, Shantou (CN)

(72) Inventor: **Shijun Lin**, Shantou (CN)

(**) Term: **15 Years**

(21) Appl. No.: **29/832,133**

(22) Filed: **Mar. 24, 2022**

(51) LOC (14) Cl. **21-01**

(52) U.S. Cl.

USPC **D21/574**; D21/570

CLAIM

The ornamental design for a toy gun, as shown and described.

DESCRIPTION

FIG. 1 is a first perspective view of a toy gun showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

(Continued)

The broken lines shown in the drawings depict portions of the toy gun that form no part of the claimed design.

1 Claim, 8 Drawing Sheets
